UNITED STATES PATENT OFFICE

WILLIAM H. JONES, OF CHICAGO, ILLINOIS

FOUNTAIN DISPLAY AND ADVERTISING DEVICE

Application filed September 1, 1928. Serial No. 303,447.

This invention relates to display and advertising devices adapted to be used in soft drink parlors or soda fountains for advertising orange, pineapple or other drinks, and it 5 consists of a novel illuminated display with sign devices for advertising matter, flashing lights, and a fountain with continuously circulated water and a rotating object or ball which may depict an orange, a pineapple or other object with which it is used. However, it is to be understood that the device is not limited for advertising drinks, such as 10 orange beverage.

Another object of the invention is to provide 15 a novel arrangement of display structure including a fountain with a double series of sprays or streams associated with a central cone or globe, the water returning to a pan from which it is pumped and circulated to 20 again be forced from the fountain rings, the device embodying a frame including a base with uprights upon which may be arranged lights adapted to flash if desired and a cover in the form of an inverted fountain pan or 25 basin upon which is arranged a motor designed to turn a revolving ball or other object which may simulate the fruit used in the beverage or other object which it is desired to advertise.

30 Other objects and advantages will be apparent as the description proceeds.

In the accompanying drawing, Figure 1 is a vertical sectional elevation of the device.

Figure 2 is a horizontal sectional view 35 taken on the line 2—2 of Figure 1.

Figure 3 is a horizontal sectional view enlarged taken on the line 3—3 of Figure 1.

Figure 4 is a horizontal sectional view taken on the line 4—4 of Figure 1 and also enlarged.

40 Figure 5 is a sectional view taken on the section line 5—5 of Figure 4.

Figure 6 is an enlarged view looking downwardly in Figure 4.

Figure 7 is a sectional view taken on the 45 line 7—7 of Figure 6.

Figure 8 is a sectional view taken on the line 8—8 of Figure 6.

Figure 9 is a detailed sectional view showing the manner of supporting the revolving ball so that it may be readily detached or 50 replaced with another object.

Figure 10 is a modification of the structure shown in Figure 9 for the same purpose, and

Figure 11 is a diagrammatic view of the circuit including the resistance elements, 55 lights and flashes forming a part of the device.

Referring to the drawings in detail, in which like reference characters designate corresponding parts throughout the several views, the device consists of a frame including a base plate 1 upon which are mounted uprights, preferably corner uprights, four in number designated at 2 and preferably of tubular formation mounted in sockets 3 at the bottom to attach to the base. Supported 60 on the uprights 2 is a fountain basin or pan 4 having a depressed central portion 5 and a flange 6, the outer upper portion of which extends horizontally to facilitate the attachment and connection of the uprights 3. On the upper ends of the uprights 3, electric 65 lights 7 are provided which may have interposed flash button 8 causing these lights to be intermittently illuminated and extinguished. The circuit comprising these lamps will be 70 later described.

It should also be noted that the lamps are arranged above an inverted pan or cover 9 which is mounted on the upper ends of the uprights so that the central portion 10 will 75 project upwardly for supporting a circular rim or box 11 which may be square or other shape and having a top 12 through which or through one side of which access may be had to a motor 13 mounted therein. This motor 80 is adapted through a coupling 14 and a worm drive gear or train 15 to rotate a vertical shaft 16 depending from a ball or other object 85 17 mounted thereabove. This object may depict an orange, a pineapple or other object 90

to be advertised and painted or ornamented accordingly. The shaft is adapted to extend into the gear 18 and into a suitable socket bearing or sleeve 19 bolted or otherwise fastened as indicated at 20 to the top 10, and may be secured in position by a set screw 21 passing through the hub of the gear 18, or as distinguished from the structure shown in Figures 1, 2 and 9, and as shown more particularly in Figure 10 of the drawing, the shaft or rod 16 may have a socket 22 in its lower end formed with a diametrical slot 23 so as to engage the upper end of a shaft 24 secured by a set screw 25 to the gear 18 through the hub or sleeve thereof and set upon a diametrical cross pin 26 with its ends projecting into the slot 23 so that the object 17 will be rotated, but may be readily displaced if desired.

20 The lower portion of the device, that is between the base 1 and the pan 6 constitutes a display compartment including a frame having upper and lower grooved members 27 and 28 adapted to receive glass or other panels 29 of a translucent or transparent nature or otherwise, upon which suitable wording may be printed or painted to advertise the goods. One side is provided with guideways at the top and bottom as indicated at 30 to take a 30 removable panel 31 constituting a door for obtaining access to the interior compartment. To reinforce the corners of the bottom compartment I provide angle iron braces or corner pieces 32 having screws or other securing 35 means 33 extending therethrough into the uprights and securing the panels in position. Any suitable number of electric lamps 34 may be arranged upon the base within the bottom compartment for illuminating the advertising matter upon the translucent or other panels 29.

In addition, lamps 35 are suspended from the portion 10 of the top or cover member 9 as indicated at 36 and a suitable angle brace 45 37 may be provided in the form of a metal strip reinforcing the members 11 and 12, to which the latter parts are secured. These lamps 35 depend within the cover above the fountain to be further explained.

50 Within the pan 5 is provided an upstanding wall or ring 38 fencing off the inner portion of the pan and open at the top for supporting therein an electric lamp 39 arranged in the socket 40. The wall 38 has a suitable 55 flange 41 supporting a bowl or other cone shaped member 42, which, however, may be of any suitable ornamentation or figure other than a cone 43 shown supported thereon to deflect the sprays of water playing thereon and 60 to prevent splashing of the water from the streams. The globe is preferably of glass so that the lamp 39 will be visible therethrough, and in this connection it may be pointed out that various colored lamps may be employed 65 so as to give different color effects. The foun-

tain includes an inner ring 44 and an outer lower ring 45 both arranged near the top of the basin portion 5 of the pan adjacent its rim and having a series of openings or teats forming nozzles 46 through which the water is forced in little streams as indicated by the dotted lines in Figure 1 of the drawing. This is effected by connecting to the rings 44 and 45, a suitable pump, preferably a rotary pump 47 arranged in the basin compartment beneath the pan 5 and connected to a motor 48 which may be suitably suspended or supported in the base compartment or upon the base 1 so as to drive the pump. It has a drain 49 and an outlet 50 discharging into the outer ring, from which leads a branch 51 extending to the inner ring by a coupling or connection 52, the inlet being controlled in each instance by a valve 53 so that the strength of the supply and streams may be readily controlled before entering the rings and being discharged from the nozzles 46 heretofore described. The water playing upon the bowl or ornamental member designated as a cone, returns to the pan 5, from which it is returned through the outlet 54 to the pump, for which it constitutes an inlet. By this means, a quantity of water may be placed in the pan and continuously circulated, thereby requiring no consumption of water from the main except that which is in the pan. This naturally does away with pipe connections to the main. The operation of the motor is controlled by a resistance element or rheostat 55 also mounted in the base compartment and like the motor and pump, shown suspended from the pan 5, so as to place suitable resistance in the circuit. This is controlled by an adjustable contact member 56 arranged on a bar 57 suspended by hangers 58 shown in the form of a U-shaped bracket attached to the bottom of the pan 5. The windings on the resistance or rheostat 55 engaged by the contact member 59 of course, constitute a variable resistance in the circuit. This contact member is preferably in the form of a fork with a roller constituting the contact member 59 journaled therein, as indicated at 60 in Figure 8 of the drawing. Screws 61 serve to secure the bar 57 in position so as to permit convenient disassembly or detachment and disconnection of the parts.

The circuit arrangement including the lamps is designated in Figure 11, in which an ordinary plug 62 for plugging in the light socket of a house wiring is shown, from which lead the conductors 63 and 64 in which the lamps 34 are interposed. The wires then lead to the motor 13 and then to the lamp 7 and also to the lamp 35 through the branch conductors 65 and 66. Branch conductors 67 and 68 lead from the conductors 63 and 64 through a conductor 68' to the variable resistance 55 and through a conductor 69 to the motor 48 from one contact of which a con-

ductor 70 leads through the movable contact 56 heretofore described. The wires 67 and 68 also lead to the lamp 39 through the flashers or interruptors 71 including variable contact members as shown so that different colored illumination may be provided within the bowl or ornamental device indicated at 42 and 43 thereby giving a very attractive color display intermittently operated as the sprays or streams of the fountain are played upon the cone or bowl, while the object or ball designating an orange or other member 17 rotates at the top.

From the foregoing description, it will be seen that I have provided a very attractive sign and advertising display device or fountain, which can be effectively used for advertising purposes, can be economically manufactured and which is not likely to get out of working order.

While I have described my invention and shown the device in the preferred form, it is to be understood that various modifications and changes in the form, arrangement and construction as well as the proportion of the parts may be made without departing from the spirit and scope of the invention.

What I claim is:

1. In an advertising and display device, a frame including a base member, uprights thereon, a fountain pan supported within the frame having sprays mounted therein, a central illuminated globe, means for circulating the water from within the pan over the globe, the portion of the frame beneath the pan being enclosed by panels housing the circulating means, illuminating devices in the base compartment beneath the pan enclosed by the panels, illuminating devices supported on the uprights, a cover arranged on the uprights, illuminating devices arranged beneath the cover, and a rotatable displaying device operable in the circuit with the lamps above the cover.

2. In an advertising and display device, a frame including a base member, uprights thereon, a fountain pan supported within the frame having sprays mounted therein, a central illuminated globe, means for circulating the water from within the pan over the globe, the portion of the frame beneath the pan being enclosed by panels housing the circulating means, illuminating devices in the base compartment beneath the pan enclosed by the panels, illuminating devices supported on the uprights, a cover arranged on the uprights, illuminating devices arranged beneath the cover, a box arranged upon the cover, a motor therein driven in the circuit with the lamps, and an ornamental object operatively connected to and extending above the motor box to be driven by the motor.

3. In an advertising and display device, a frame including a base, uprights mounted on

the base, corner members on the uprights and base, advertising panels between said corner members and uprights, one of said panels constituting means for obtaining access to the compartment thus formed, a pan supported by the uprights, a division wall in the pan, said pan adapted to receive water or other fluid around the division wall to be circulated, conduits mounted within the pan and having nozzles projecting upwardly, a globe supported on the division wall, a cone on the globe and upon which certain of the streams are played from the nozzles, a pump having an inlet connected to the bottom of the pan and an outlet connected to the conduits for discharging water into the conduits as the pump is operated, and means for controlling the force of the streams exuding from the nozzles.

4. In an advertising and display device, a frame including a base, uprights mounted on the base, corner members on the uprights and base, advertising panels between said corner members and uprights, one of said panels constituting means for obtaining access to the compartment thus formed, a pan supported by the uprights, a division wall in the pan, said pan adapted to receive water or other fluid to be circulated, conduits mounted within the pan and having nozzles projecting upwardly, a globe supported on the division wall, a cone on the globe and upon which certain of the streams are played from the nozzles, a pump having an inlet connected to the bottom of the pan and an outlet connected to the conduits for discharging water into the conduits as the pump is operated, the outlet of the pump extending to the independent conduits, valves controlling said outlet to the conduits and the pressure of the water forced into the same for controlling the height of the streams forced from the nozzles onto the globe, and means for controlling the operation of the pump.

5. In an advertising and display device, a frame including a base, uprights mounted on the base, corner members on the uprights and base, panels between said corner members and uprights, one of said panels constituting means for obtaining access to the compartment thus formed, a pan supported by the uprights, a division wall in the pan, said pan adapted to receive water or other fluid to be circulated, conduits mounted within the pan and having nozzles projecting upwardly, a globe supported on the division wall and upon which streams are played from the nozzles, a pump having an inlet connected to the bottom of the pan and an outlet connected to the conduits for discharging water into the conduits as the pump is operated, the outlet of the pump extending to the independent conduits, valves controlling said outlet to the conduits and the pressure of the water forced into the same for controlling

the height of the streams forced from the nozzles onto the globe, an electric motor connected to the pump, a variable resistance controlling said motor in circuit therewith, 5 lamps in said circuit mounted in the base compartment between the pan and the base, lamps mounted upon the uprights, a cover arranged upon the uprights above the globe, lamps beneath said cover, means for flashing 10 said lights, a compartment arranged above the cover, a motor housed therein, said motor being included in the circuit, a gearing connected with the motor, a shaft journaled in the bearing on the cover, and an object above 15 the box having a depending rod detachably engaged in the bearing and with the gear to be driven thereby during the flashing of the lamps and operation of the fountain streams.

6. In an advertising and display device, a 20 frame including a base member, a fountain pan supported within the frame and having sprays mounted therein, a partition within the pan and dividing the central portion thereof from the outer portion, a globe supported on and around the upper portion of 25 the partition, illuminating means supported on the pan within the partition and under the globe for illuminating the latter, means for circulating fluid from within the pan 30 over the globe, illuminating sign panels beneath the pan and enclosing the circulating means, a cover supported in spaced relation above the pan and globe, and illuminating devices beneath the cover to direct light rays 35 downwardly on to the pan, globe and fluid circulated over the globe.

7. In an advertising and display device, a frame including a base member, a fountain pan supported within the frame and having 40 sprays mounted therein, a partition within the pan dividing the central portion thereof from the outer portion, a globe supported on and around the upper portion of the partition, illuminating means supported on the 45 pan within the partition and under the globe for illuminating the latter, means for circulating fluid from within the pan over the globe, illuminated sign panels beneath the pan and enclosing the circulating means, a 50 cover supported in spaced relation above the pan and globe, illuminating devices on the cover for directing light rays upwardly, and a movable advertising device supported on the cover and illuminated by said last-mentioned 55 illuminating devices, said advertising device being in circuit with the illuminating devices and circulating means.

8. In an advertising and display device, a frame including a base member, an illuminated member supported centrally over the base member, means for circulating fluid in streams upwardly against and over the illuminated member, a cover on the frame, a compartment on the cover, illuminating devices above and below the cover, a motor 65

mounted within the compartment in circuit with the illuminating means and having a vertical bearing socket, and a display device having a depending rod rotatable in the socket and operatively connected detachably 70 to the motor to be driven thereby, whereby said display device may be substituted by another display device, said display device being illuminated by the illuminating means above the cover.

In testimony whereof I affix my signature.
WILLIAM H. JONES.
